UNITED STATES PATENT OFFICE.

RICHARD VARLEY, OF ENGLEWOOD, NEW JERSEY, ASSIGNOR TO VARLEY DUPLEX MAGNET CO., A CORPORATION OF NEW JERSEY.

INDUCTION-COIL AND BOX FOR EXPLOSION-ENGINES.

No. 875,472.

Specification of Letters Patent.

Patented Dec. 31, 1907.

Application filed July 24, 1907. Serial No. 385,378.

To all whom it may concern:

Be it known that I, RICHARD VARLEY, a citizen of the United States, residing at Englewood, in the county of Bergen and 5 State of New Jersey, have invented certain new and useful Improvements in Induction-Coils and Boxes for Explosion-Engines, of which the following is a full, clear, and exact description.

- 10 My invention relates to a form of coil construction or box for use with explosion engines, particularly multiple cylinder engines of the type used in motor cars and automobiles.
- 15 The purpose of the invention is to improve the construction in various features thereof, and particularly to provide a compact, efficient and easily constructed type of coil unit and box having the theoretical principles and 20 characteristics set forth in my companion application, Serial No. 382,488, filed July 6, 1907.

In my companion application above referred to I have fully set forth and described 25 the action of a plurality of induction coils when grouped side by side in firing a multiple cylinder engine. In said application it is shown that with a crank shaft of certain form, that an uncompressed charge sometimes 30 exists in the cylinder or cylinders immediately adjacent to one which is at that moment being fired, and that furthermore there sometimes exists when the engine is heavily loaded, a condition by which cross 35 induction occurs between adjacent coils so that an acting coil produces a feeble discharge in a neighboring coil, but sufficiently intense in special circumstances to fire the uncompressed charge occurring as mentioned. 40 In the said application there are pointed out arrangements by which this difficulty can be overcome. In the present application a particular coil box with the coil units, as an article of manufacture is shown, and which fulfils all requirements 45 with regard to preventing cross induction between adjacent coils.

By the present invention the secondary windings are insured against injury by excessive potentials therein which might arise 50 when they are wholly open circuited, and certain other practical and advantageous features secured, as will be later pointed out.

With these various objects in view the invention consists in the features of construc-

tion and combination hereinafter set forth and claimed.

In the drawings: Figure 1 is a perspective view showing a single coil or unit embodying the principles of my invention; Fig. 2 is a 60 top or plan view of a coil box showing the coil units assembled therein; Fig. 3 is a perspective view illustrating certain parts of the coil or unit and the manner in which they are assembled; and Fig. 4 is a sectional view on 65 the line IV—IV of Fig. 2.

Referring to the drawings in which like parts are designated by the same reference sign, 1 indicates the containing box and 2 the various coils or units adapted to be assembled therein. The box has a rabbeted outer edge 3, to receive any suitable cover 4, and shed water therefrom away from the interior of the box. The various coils or units 2 are of rectangular transverse section and of such 75 a size as to closely fit the containing box 1 when assembled side by side therein, as shown in Fig. 2. In accordance with the present invention the various coils or units have individual casings constructed of mag- 80 netic and non-magnetic material, such as iron and wood, in the manner shown in Fig. 3.

5 indicates a piece of sheet iron, sheet steel or other paramagnetic material, bent into 85 U-shaped form in transverse section, and having a length corresponding to the desired length of the completed coil.

6 denotes a wooden frame of inverted L-shaped section, and it is evident that this 90 may be assembled with the sheet iron part 5 so as to form a complete coil casing open at its lower end. The upper lateral extension 7 of the frame 6 constitutes the top of the completed coil casing. This plate is perforated with an opening 8, to receive the iron core of the coil, and with various smaller holes 9, to receive screws or fastening devices for the various vibrator and terminal parts and connections. The coil 10 is inserted into this casing through the lower open end thereof, as shown in Fig. 4, so that the core 11 projects through the hole 8 of the top plate 7.

12 indicates a filling of wax or suitable insulating material around the coil to hold the same firmly and permanently in place.

6^a indicates a block or plate forming the bottom of the casing.

The usual condenser is shown at 12^a. 110

The induction coil 10 is of the ordinary sort having primary and secondary windings, and in accordance with my present invention, one terminal of each is connected or 5 grounded upon the sheet iron part 5. These connections are indicated by the dotted lines 13 and 14 at the right hand coil in Fig. 2. The other terminals of the respective windings run to certain vibrator mechanism 10 and terminal binding posts hereinafter described.

The sheet iron part 5 being made a terminal of the primary and secondary windings, it becomes necessary to provide means for 15 establishing a good electric connection with this sheet iron part from the current source employed. For this purpose I provide a metallic plate or strip 15, which is permanently screwed or secured within the coil box 20 1 along the front upper inside edge thereof. The top edge of this strip 15 is notched at a plurality of points 16, corresponding to each of the coil units, and preferably at opposite side edges or corners of the same. 25 17 indicate bars within the coil casings located at the corners of the U-shaped sheet iron piece 5. These bars 17 have threaded holes to receive screws 18, the position and separation of which accords to the location 30 of the notches 16 above described.

19 indicates a bent-over sheet metal plate at the upper edge of the coil casing, and which is designed to present a more perfectly finished metallic front face than the 35 sheet iron part 5, which may be japanned or lacquered to give it a better appearance. When the coils are dropped in the box 1, the screws 18 fall in the notches 16 of the strip 15, and when they are tightened, the metallic plate 19 is drawn into close electrical 40 contact with the strip 15. The plate 19 being in soldered or permanent connection with the part 5, it is clear that the primary and secondary terminals 13 and 14 of all the coils 45 are in this way efficiently connected to the common battery strip 15.

Each coil has a vibrator, including a bridge 50 20, and a spring blade or trembler 21. The bridge 20 is permanently connected with the ungrounded primary terminal 22 (see Fig. 2), and the blade or trembler 21 is fixed to a metallic base 23, which carries a binding post 24, for the wire leading to the circuit controller. In addition to these parts there is 55 an insulating block 25, permanently attached to the top plate 7 of the coil casing. This insulating block has a small metallic plate 26 on its upper face, secured thereto by a single screw 27, and one or more pins 28. The attachment of the block 25 to the coil casing 60 plate 7 is made by screws 29, extending upward from the under side thereof, and not in alignment with the screw 27. A further point in this construction is that none of the 65 screws 27 or 29 extends completely through

the insulating block 25. These precautions are necessary, because the plate 26 is made the terminal of the ungrounded secondary winding by a connection 30 (see Fig. 2), which leads to a binding post 31, on said 70 plate 26. The distance of the plate 26 from the metallic casing 5 and from the bridge 20 therefore determines the maximum possible spark gap through which the secondary winding will discharge. This maximum 75 spark gap is made absolutely definite by the prongs or extensions 32 and 33, which extend toward one another respectively from the plate 26 and from the sheet iron casing 5. The insulating block 25 is grooved or cut 80 away adjacent these points in the manner clearly shown at 34, in Fig. 1.

The above construction is an important and advantageous one in practice, since the secondary winding of the coil is liable to become unduly strained by the electrical tension which is developed therein in case the coil should be operated with its secondary circuit open or with an unduly great spark gap. The arrangement of the plate 26 determines the maximum possible spark gap as the distance between the points 32 and 33, so that it is impossible for the insulation to become strained, even in case the spark plug connection becomes loose and allows the wire 95 to fall away therefrom and wholly open the secondary circuit at this point.

A feature of the invention lies in the arrangement by which the coil box is kept absolutely water tight. I provide a plurality 100 of holes 35 and 36, leading upward through the rear wall or edge of the coil box 1, at a point within the rabbet 3. At an adequate distance, several inches below the upper edge of the coil box, these holes join a broad laterally extending groove 37 deeply cut across the rear outside face of the box. The circuit wires leading to the spark plugs and the circuit controller pass into the rear of the box 105 through these holes and upward through the edge of the box where they are joined to the binding posts 24 and 31 respectively. It is evident that when the cover is in place, as shown in Fig. 4, there is no possibility of water finding its way into the box through the 110 openings for the circuit wires. When these circuit connections are made in this way, and the coils have been properly tightened in the box 1 by the various screws 18, it is evident 115 that they are ready for operation. If at any time it becomes necessary to replace a coil for any purpose this is quickly done by loosening the screws 18 and removing the circuit connections of the coil at the binding posts 24 and 31.

By reason of the construction of the coils having the sheet iron part 5 forming the main part of their containing casing, the coils are magnetically shielded from one another. It is accordingly impossible for cross induc- 120 125 130

tion to take place between such adjacent coils and under such circumstances as to produce harmful or improper firing in the manner fully set forth in my companion case 5 above referred to and which has been briefly touched upon in the preliminary part of this specification. But although cross firing is wholly prevented, the presence of the iron part 5 does not affect injuriously the action

10 of the coil, because the casing is not made metallically continuous completely around the coil, being interrupted at the rear side thereof by the wooden back or frame 6. If desired a small sheet iron plate 5^a may be 15 placed at the bottom of the coil casing and resting on the bottom plate 6^a to further increase the magnetic shielding effect indicated.

What I claim, is:—

1. An induction coil unit for explosion 20 engines comprising a **U**-shaped sheet of paramagnetic material, an **L**-shaped frame assembled therewith to form a casing, and an induction coil within such casing.

2. An induction coil unit for explosion 25 engines, comprising a paramagnetic casing of sheet material having an open side, and an induction coil within the casing.

3. An induction coil unit for explosion engines, comprising a casing including a **U**- 30 shaped sheet iron part, and a non-magnetic frame assembled therewith to form a casing, and an induction coil within such casing.

4. An induction coil unit for explosion engines, comprising a casing having a **U**- 35 shaped sheet of paramagnetic material embodied therein, and an induction coil within such casing.

5. An induction coil unit for explosion engines, comprising a casing having three of 40 its sides formed of a single piece of paramagnetic sheet material, and an induction coil within such casing and having its primary and secondary windings grounded on said paramagnetic sheet material.

45 6. In an induction coil unit, a casing having one or more of its sides formed of paramagnetic sheet material, an induction coil within such casing and having its primary and secondary windings grounded on said 50 paramagnetic sheet material, and a plate connected to the other secondary terminal and separated in a predetermined spaced apart relation from said paramagnetic sheet material, so as to establish a spark gap in 55 connection therewith.

7. In an induction coil unit, a casing comprising a **U**-shaped sheet of paramagnetic material and an **L**-shaped non-magnetic part 60 assembled together to form a casing, an induction coil within such casing and having

its primary and secondary windings grounded on said part of paramagnetic material, and an insulating block secured on the casing, a plate fixed to said block and connected to the ungrounded secondary terminal of said coil, said plate having a portion projecting toward said part of paramagnetic material and establishing a spark gap in connection therewith. 5

8. In combination, a plurality of induction coil units, each having a casing of paramagnetic material, the coil box having a metallic strip along one edge thereof, and clamping means for engaging and electrically connecting said casing on said strip. 70

9. In combination, a plurality of induction coil units, each having a casing of paramagnetic material forming one primary terminal, and a coil box having a metallic strip secured on one inside edge thereof, the upper 80 edge of said strip being notched, and clamping means passed through said notches and engaging said coil units to electrically and mechanically connect said casings on said strip. 85

10. In combination, a plurality of induction coil units, each having a casing of paramagnetic material, said casing forming a terminal for the primary winding, a coil box having a metallic strip, and means engaging 90 said casings for clamping and electrically connecting them to said strip. 90

11. In combination, a plurality of coil units, each having a primary and a secondary terminal binding post, and a coil box 95 having a rabbeted edge said edge being vertically perforated inside of said rabbet whereby the terminal wires from said coils may be led out of the box through said holes in water proof relation. 100

12. In combination, a plurality of coil units each having a casing of paramagnetic material and having primary and secondary terminal wires, a coil box having a rabbeted edge said box having holes extending downward in said edge inside said rabbet and adapted to receive said terminal wires, a cover for said box co-operating with said rabbet to inclose said coil units, and their terminal wires in water-proof relation, and means 105 for establishing connection with the primary and secondary windings of all the coils through their casings of paramagnetic material. 110

In witness whereof, I subscribe my signature, in the presence of two witnesses.

RICHARD VARLEY.
